US00D851156S

(12) **United States Design Patent** (10) **Patent No.:** **US D851,156 S**
(45) **Date of Patent:** **** Jun. 11, 2019**

(54) **VIDEO ANALYTICS DEVICE**

(71) Applicant: **NetraDyne, Inc.**, San Diego, CA (US)

(72) Inventors: **Sandeep Pandya**, San Diego, CA (US);
Adam David Kahn, San Diego, CA (US);
Lance Steven Hetherington, Encinitas, CA (US); **Michael Campos**, La Jolla, CA (US); **David Jonathan Julian**, San Diego, CA (US);
Tejeswara Rao Gudena, Bangalore (IN); **Avneesh Agrawal**, Bangalore (IN)

(73) Assignee: **NetraDyne, Inc.**, San Diego, CA (US)

(**) Term: **15 Years**

(21) Appl. No.: **29/624,165**

(22) Filed: **Oct. 30, 2017**

(51) LOC (11) Cl. **16-05**

(52) U.S. Cl.

USPC **D16/219**; D16/218

(58) **Field of Classification Search**

USPC D16/200, 202-204, 208, 210, 218, 219;

(57)

CLAIM

The ornamental design for a video analytics device, as shown and described.

DESCRIPTION

FIG. 1 is a top front perspective view of a video analytics device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the video analytics device in which the design is embodied that form no part of the claimed design. Additionally, the dash-dot lines denote the boundary of the claim and form no part of the claimed design.

1 Claim, 6 Drawing Sheets
